(57) CLAIM

I claim the ornamental design for the temperature-retaining holder for foods, as shown and described.

DESCRIPTION

FIG. 1 is a top plan view of a temperature-retaining holder for foods showing my new design, shown in an unwrapped state.

FIG. 2 is a top perspective view thereof.

FIG. 3 is a top perspective view thereof, shown partially wrapped.

FIG. 4 is a top perspective view thereof, shown partially wrapped.

FIG. 5 is a top perspective view thereof, shown partially wrapped.

FIG. 6 is a top perspective view thereof, fully wrapped.

FIG. 7 is a right side view of FIG. 6.

FIG. 8 is a left side view of FIG. 6.

FIG. 9 is a front view of FIG. 6; and,

FIG. 10 is a rear view of FIG. 6.

The broken lines are for illustrative purposes only and form no part of the claimed design.
